HANDLE FOR TABLE FLATWARE

Armand M. Guior, New York, N. Y., assignor to Imperial Dania Silver Corp., New York, N. Y.

Application November 18, 1949, Serial No. 6,110

Term of patent 14 years

(Cl. D54—12)

To all whom it may concern:

Be it known that I, Armand M. Guior, a citizen of the United States and resident of the city, county, and State of New York, have invented a certain new, original, and ornamental Design for a Handle for Table Flatware, of which the following is a specification, reference being had to the accompanying drawing, forming part thereof:

Fig. 1 is a front elevational view of a handle for table flatware showing my new design;

Fig. 2 is a side view thereof; and

Fig. 3 is a top view thereof.

The rear of the handle not shown in the drawing is the same as the front view thereof that is shown and the side of the handle not shown is the same as the side shown.

I claim:

The ornamental design for a handle for table flatware, substantially as shown and described.

ARMAND M. GUIOR.
